US0D1076912S

(12) **United States Design Patent** (10) **Patent No.:** **US D1,076,912 S**
(45) **Date of Patent:** **** May 27, 2025**

(54) **VIRTUAL REALITY GLASSES FRAME**

(71) Applicant: **Beijing Zitiao Network Technology Co., Ltd.**, Beijing (CN)

(72) Inventor: **Jinbo Huang**, Beijing (CN)

(73) Assignee: **Beijing Zitiao Network Technology Co., Ltd.**, Beijing (CN)

(**) Term: **15 Years**

(21) Appl. No.: **29/885,394**

(22) Filed: **Feb. 23, 2023**

(30) **Foreign Application Priority Data**

Aug. 26, 2022 (CN) 202230561774.7

(51) **LOC (15) Cl.** **14-02**

(52) **U.S. Cl.**

USPC **D14/372**

(58) **Field of Classification Search**

(57) **CLAIM**

The ornamental design for a virtual reality glasses frame, as shown and described.

DESCRIPTION

FIG. 1 is a perspective view of a VR glasses frame showing the new design;

FIG. 2 is another perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown in the drawings illustrate portions of the article that form no part of the claimed design.

1 Claim, 5 Drawing Sheets
